UNITED STATES PATENT OFFICE.

HARRY IRVING STRAINING, OF KNOXVILLE, TENNESSEE.

RAIL JOINT.

Application filed March 16, 1922. Serial No. 544,118.

To all whom it may concern:

Be it known that I, HARRY I. STRAINING, a citizen of the United States, residing at Knoxville, in the county of Knox and State 5 of Tennessee, have invented a new and useful Improvement in Rail Joints, of which the following is a specification, reference being had to the accompanying drawing.

My improvement relates particularly to 10 railway rail joint structures wherein provision is made for holding nuts on the rail joint bolts against turning movement after the nuts have been set.

The object of the invention is to provide 15 such a structure comprising parts which are easily assembled and effective after they have been assembled. In my improved structure, the members which engage the nuts are to be applied after the bolts and 20 nuts have been applied and set.

In the accompanying drawings,

Fig. 1 is a side elevation of a joint formed at the meeting ends of two rails and embodying my structure;

25 Fig. 2 is a plan of the same structure, the right hand part being sectioned horizontally on the line, 2—2, of Fig. 1;

Fig. 3 is an upright section on the line, 3—3, of Fig. 2, looking toward the right;

30 Fig. 4 is a section on the line, 4—4, of Fig. 3, looking toward the left;

Fig. 5 is a plan of one of the bolts;

Fig. 6 is a perspective of one of the locking plates;

35 Fig. 7 is a transverse section on the line, 7—7, of Fig. 5, looking toward the right.

Referring to said drawings, A, A, are ordinary track rails having a foot, A¹, a web, A², and a head, A³. These rails meet 40 end-to-end in the usual manner.

Fish plates, B, rest against the opposite sides of the rails and extend across the joint in the usual manner. The upper edge of each fish plate bears against the lower 45 face of the adjacent part of the head, A³, and the lower part of such plate engages the foot, A¹. Each plate has four horizontal, transverse apertures, B¹, to receive the bolts. Each rail has apertures, A⁴, in alignment 50 with the apertures, B¹, of the fish plates.

The fish-plates are joined to the rails by means of bolts, C. Each bolt, C, comprises a cylindrical shaft, C¹, which is screw-threaded at one end. On the other end is 55 a head, C², which, in the form shown, is cylindrical. At the side of said head to-

ward the threaded end is an elliptical or non-cylindrical enlargement, C³, which extends into the adjacent aperture, B¹, which is, as above stated, horizontally elongated, 60 and said aperture being small enough to prevent turning of the enlargement, C³, in said aperture, whereby the bolt is held against turning when a wrench is applied to the nut, C⁷, for turning the latter. On 65 the head opposite the enlargement, C³, is a horizontal extension, C⁴, which has a transverse aperture, C⁵, adapted to receive a cotter or cross pin or similar retaining member, C⁶. The nut, C⁷, is applied to the threaded 70 end of the bolt and is turned until it bears against the adjacent fish plate and the head of the same bolt is drawn against the outer face of the opposite fish plate, the nut being 75 drawn as tightly as is required for good service, the turning stopping when the nut is in position to receive the jaws of one of the locking plates described below.

The two bolts at the same side of the joint are alternated in direction, so that a 80 bolt head and a nut will be on the outer face of each fish plate at each side of the meeting ends of the rails.

After the bolts have been put into position and the nuts have been securely tightened 85 to the desired extent, four locking plates, D, are applied. Each plate has at one end a horizontal, transverse aperture, D¹, and jaws, D², at the other end. The locking plate is moved horizontally toward the fish 90 plate, the plate being so held as to cause the bolt extension, C⁴, to enter and extend through the aperture, D¹, while the adjacent nut, C⁷, extends between the jaws, D². After the plate has been put into that position, a cotter or cross pin, C⁶, is extended 95 through the cotter aperture, C⁵. Said aperture is preferably elongated in the direction of the length of the bolt, in order to adapt it to receive a broadened cross pin which will force the locking plate, D, against the head, C², of the bolt. As shown in Figs. 2 and 6, the locking plate has an offset, D³, which permits the end having the jaws to bear flatwise against the fish plate while the end having the aperture, D¹, bears flatwise against the bolt head, C².

When the parts have been thus assembled, the structure is complete, and all the nuts are held against turning.

It is to be emphasized, that by the use of the extension, C⁴, of the bolt, each bolt

can be put into position and its nut applied without reference to the locking plate; that the locking plate is not to be engaged or held by one of the bolts while the bolts are being applied or secured; that, on the contrary, the bolts and nuts are to be fully placed and secured before the locking plates are placed, and that then the locking plates are put into position without disturbing the bolts and nuts.

I claim as my invention,

1. As articles of manufacture for use in forming railway rail joints, a bolt comprising a stem threaded at one end and having a head at the other end and an extension on said head formed to receive a retaining member, and a locking plate formed at one end to receive said extension and formed at the other end to adapt it to make engagement with a nut, substantially as described.

2. As articles of manufacture for use in forming railway rail joints, a bolt comprising a stem threaded at one end and having a head at the other end and having at the side of the head toward the threaded end a non-circular enlargement and having at the other side of the head an extension formed to receive a retaining member, and a locking plate formed at one end to receive said

extension and formed at the other end to adapt it to make engagement with a nut, substantially as described.

3. As articles of manufacture for use in forming railway rail joints, a bolt comprising a stem threaded at one end and having a head at the other end and a transversely apertured extension on said head, and a locking plate formed at one end to receive said extension and formed at the other end to adapt it to make engagement with a nut, substantially as described.

4. As articles of manufacture for use in forming railway rail joints, a bolt comprising a stem threaded at one end and having a head at the other end and having at the side of the head toward the threaded end a non-circular enlargement and having a transversely apertured extension on the other side of the head, and a locking plate formed at one end to receive said extension and formed at the other end to adapt it to make engagement with a nut, substantially as described.

In testimony whereof I have signed my name, this 11th day of March, in the year 55 one thousand nine hundred and twenty-two.

HARRY IRVING STRAINING.
